FIG. 1

FIG. 2

FIG. 3

FIGURE 1 is a perspective view of a bowl for a toilet or similar article embodying my new design;

FIGURE 2 is a top plan view of the design of FIG. 1; and

FIGURE 3 is a front elevation as seen from the right in FIG. 1.

The dominant features of my design reside in the portions shown in full lines.

The hidden side of the over-all outline and of the bowl are mirror images of the side shown and the hidden side of the base is decorated similarly to the front with a continuing random pattern of overlying fronds as evidenced by the partial view thereof in FIGURE 3.

The side of the bowl opposite that shown in FIG. 1 is a mirror image thereof. The portion shown in phantom lines is shown for illustrative purposes only.

I claim:

The ornamental design for a bowl for a toilet or similar article, as shown and described.
